END LABELING ATTACHMENT

William Hoppe, Longmeadow, and Franklin B. Roberts, West Springfield, Mass., assignors to National Bread Wrapping Machine Co., Springfield, Mass., a corporation of Massachusetts

Application March 20, 1941, Serial No. 384,374

14 Claims. (Cl. 216—25)

This invention relates to end labeling devices particularly intended for association with a wrapping machine in which an article such as a loaf of bread is heat sealed in a wrapper of waxed paper or the like, to the outside of which the label is to be secured. One object of the invention is to improve the manner of feeding the labels in web form from a reel, severing individual labels from the web, and feeding the severed labels into registry with the wrapped articles. A further object is to improve the mechanism for registering the labels with respect to the articles. A further object is to improve the mechanism for sealing the labels to the underlying wrapper. Additional objects will appear from the following description and claims.

Referring to the drawings,

Fig. 1 is a side elevation of a labeling device embodying the invention;

Fig. 2 is a top plan thereof;

Fig. 3 is a sectional detail plan on a larger scale;

Figs. 4 and 5 are details of the article-released mechanism for starting the labeling cycle;

Fig. 6 is a sectional elevation of the label web feed roll drive;

Fig. 7 is a sectional elevation of the control for the cut label feeding rolls;

Fig. 8 is a detail of the drive for the cut label feeding rolls;

Fig. 9 is a sectional elevation of the path of the label web and of the severing knives;

Fig. 10 is a detail of mechanism appearing in Fig. 6;

Fig. 11 is a detail on an enlarged scale of certain feed mechanism for the cut labels; and

Figs. 12, 13, and 14 are sequential views of the feeding of a cut label to the article.

The labeling attachment is shown as being adapted for mounting between a wrapping machine 20 and a cooling unit 21 (Fig. 2Q, so that if installations without the labeler are desired it can be removed and the cooling unit moved up to the wrapping machine. The frame 22 of the labeler is secured as by a pin 23 to the wrapper frame 20, and has laterally spaced bottom belts 24 and two side belts 25 (Fig. 2) which receive the wrapped articles from the delivery conveyor of the wrapping machine and forward them through the labeler. To drive these belts the shaft 26 of the bottom belt is coupled as by a chain 27 with any suitable part of the wrapping machine.

A cam shaft 28, coupled to shaft 26 by chains 29, 30, is journaled across the frame, and has at one end a sleeve loosely rotatable upon it carrying a sprocket 31, a sprocket 32, a drive ratchet 33, and a holding ratchet 34. The sprocket 31 is driven by the chain 30 from the shaft 26, keeping the sleeve in constant rotation. Sprocket 32

serves to drive the cooling attachment shaft 35 through a chain 36. A cylindrical member 37 is keyed to the shaft 28 and has a projecting journal 38 in which a stub shaft 39 is mounted. One end of this shaft has fixed to it an arm 40, which is constantly urged in a counterclockwise direction as viewed in Fig. 3 by a spring 41 compressed between the arm and a portion of the journal 38. The arm 40 is releasably held by latch mechanism controlled by the presence of a wrapped loaf as will be described below.

Also fixed to the arm 40 is a driving pawl 45 which, when the arm and shaft are rotated by the spring 41, engages the driving ratchet 33. It will be recalled that this ratchet is constantly rotated, and whenever the pawl 45 is permitted to engage with the pawl, together with the member 37, the shaft 39, and the arm 40, will be carried around with it. By mechanism to be described this rotation is limited to a single revolution until the cycle is again started by another loaf of bread. It is desirable to lock the member 37 to the drive ratchet during rotation to prevent any tendency to overrun, and for this purpose a holding pawl 46 is freely pivoted on the shaft 39. This pawl is pressed into contact with the ratchet 34 by a leaf spring 47 mounted on an arm 48 fixed to the end of shaft 39, the spring resting against a pin 49 extending laterally from the pawl 46. At times when the member 37 is stationary the ratchet turns freely under the pawl, but when the member is free to rotate the engagement of the pawl 46 and ratchet 34 prevents it from turning faster than the driving ratchet.

The shaft 28 is driven periodically, by means of the mechanism described and certain trip mechanism to be considered later, through one revolution each time a loaf is fed along by the belts. Several cams are mounted on the shaft for rotation with it, and their functions will be considered separately after first following the course of the web *w* as it leaves its supply roll 50. The web first passes under a guide roll 51 which is free to rise and fall in slots 52 formed in plates 53 secured to the frame of the labeler. The roll 51 has pinions 54 engaged with racks 55 to keep its axis always parallel during its movement. The web then passes between plates 56, the function of which will appear later, and over a roll 57 which, when adjusted, remains in a fixed position and is clamped by thumb screws 58. This roll preferably has pinions engaging racks 60 to keep its axis parallel during adjustment. After leaving roll 57 the web passes between a driven roll 61 and a mating roll 62 carried on a swinging frame 63 pivoted on the machine at 64 and pressed towards the roll 61 by a tension spring 65. The rolls are preferably circumferentially recessed at intervals as at 66 (Fig. 3), and are

geared together at 67, 68 (Fig. 6), the latter of these gears meshing with a gear 69 to which are secured a driving ratchet 70 and a holding ratchet 71. The shaft of roll 62 is preferably provided with a grasping handle 72 (Fig. 3) by which the rolls may be separated in order to permit threading of the web through them.

The rolls are driven by an oscillating pawl 75 carried upon a member 76 free to swing about the shaft 77 upon which the ratchets 70 and 71 and the gear 69 are mounted. To this member 76 is pivoted at 78 a link 79 pivoted at 80 to an arm 81 swinging on a shaft 82. A cam roll 83 on the arm 81 is held by a spring 84 against a cam 85 on the shaft 28 previously mentioned. The cam oscillates the pawl 75 in each cycle through such an arc as to rotate the feed rolls sufficiently to project the web upwardly beyond the rolls the length of one label. A pawl 86 swinging on a stationary pivot 87 engages the holding ratchet 71 to prevent retrograde movement of the feed rolls.

As the web rises above the feed rolls it passes between guide members 89, lying in the grooves 66, to direct it between a stationary cutter bar 91 and a movable cutter blade 92. The latter is pivoted at 93 to a rocker 94 swinging on a stationary pivot 95 and having an extension 96 bearing a cam roll 97. A cam 98 on shaft 28 causes periodic motion of the cutter to sever a blank from the web.

As the blank is cut from the web it is grasped by two vertical transfer rolls 100, 101, the former of which is freely rotatable upon a fixed stud 102 while the latter is journaled on a shaft 103 carried by a swinging bracket 104. This bracket is pivoted upon a stud 105, and is acted upon by a spring 106 to keep the rolls separated except when pressed together by other means; the spring being compressed between a fixed plate 107 on the bracket and a fixed part of the machine. A link 108 (Fig. 7) is pivoted to the bracket 104 and to an arm 109 having a roll 110 held against a cam 111 on shaft 28 by spring 106, the roll 101 being by this means pressed against the roll 100 at the time a label is cut off and held in such contact until the label has been delivered laterally out of the rolls. Roll 100, which does not move and therefore is in a position to engage the vertically moving web, is preferably not driven except by engagement with roll 101 in order not to cause any displacement of the label before this is gripped firmly between the two rolls. Roll 101 has a gear 115 meshing with a wide faced gear 116 on a shaft 117 coupled by links 118 and 119 with the shaft of roll 101 and with a stationary shaft 120 respectively. A gear 121 on the latter shaft meshes with the wide faced gear 116 but is laterally displaced with respect to gear 115. The linkage described permits the roll 101 to be moved back and forth while still coupled to gear 121. This latter gear is in mesh with a gear 122 (Figs. 3 and 11) loose on a vertical shaft 123. Adjacent the gear on this shaft is a sleeve 124 carrying a sprocket 125 in engagement with the chain 126 which connects the drive pulleys of the side belts at the two ends of the machine, and thus driven in timed relation to the passage of articles along the belt conveyor. Sleeve 124 has an axially movable pin 127 adapted to fit into a recess 128 in the gear 122 and held either in or out of engagement with the recess by a set screw 129. This permits the transfer rolls and certain feed belting associated with them to be disconnected when the wrapping machine is to be operated temporarily

without the labeler. In this case it is necessary to have the article feeding belts of the labeler running in order to carry the wrapped articles through the labeler to the sealer, and in order to prevent unnecessary wear the described disconnecting means has been provided.

To the gear 122 is secured the hub of a pulley 130 around which passes a belt 131. A similar belt 132 passes around a pulley coaxial with and driven from the gear 121. The two belts will therefore be driven in face contact with each other. Belt 132 passes around a terminal pulley 133 located so as to bring the belt almost in line with the side conveying belt 25. Belt 131 passes around a terminal pulley 134 that is located short of the pulley 133 and out of line with it so as to cause a sharp bend in the belts as is best seen in Figs. 12 to 14. The purpose of the bend is to cause the label to slant towards the end of the article in a direction corresponding to that in which the article is moving. The belts receive a cut label from the rolls 100, 101 and deliver it to the package as shown in Figs. 12 and 13. After receiving the label the article passes against belts 135, preferably of metal and running past a heater 136. Heat from this belt fuses the thermoplastic coating with which the label is provided and permits it to adhere to the wrapper folds at the end of the article. The article then passes to the usual delivery belts or cooler which it is not necessary to illustrate here in detail.

It remains to consider two control mechanisms, one for starting the label feed in timed relation to the passage of an article and the other for insuring the cutting of the label in correct registration with respect to its printing or design. Taking up the first the control of the label feed by the article, it should be noted that in practice the articles are fed along the discharge conveyor of the wrapping machine by contact of spaced pushers with their rear faces. The articles thus arrive in the belt conveyors of the labeler with these rear faces in timed relation to the wrapping machine but with their front faces in varying timed relationship in accordance with the width of the article in the direction of travel of the conveyor. It is one of the features of the present invention that since the feed of the label is initially upwardly the only adjustment necessary to center labels on loaves of varying widths (unless the marginal spacing is to be changed as discussed below) is to change the label web reel. It is not necessary to change the adjustment of the web feed, for this varies the feed of the web in the direction of the height, not the width, of the article. To accomplish this, however, it is necessary to time the machine automatically so that the feed of the label is in synchronism with the forward and not the rear face of the article.

The timing mechanism is under the control of a feeler 140 (Fig. 4) fixed to a rocking shaft 141 extending below the bottom belt conveyors 24, the feeler extending upwardly between the two spaced bottom conveyors. The shaft also carries an arm 142 bearing a laterally projecting pin 143. A spring 144 normally holds the feeler in the position of Fig. 4. Pivoted to a shaft 145 is a rail 146 resting on this pin and held yieldingly against it by a spring 144'. A notch 147 in the rail fits over a side lug 148 on the arm 40 and holds this against the tendency of the spring 41 to turn the arm in a direction to bring the driving pawl against its ratchet. When the rail is raised by the turning of the feeler by an article the arm 40 is freed, the driving pawl is

brought into engagement with its ratchet, and the pawl carrier and the cam shaft 28 driven by it are caused to rotate through one revolution. At the completion of one revolution the lug 148 again enters the notch 147, the feeler having been by this time released by the passage of the article beyond it, thus disengaging the pawl and ratchet and causing the shaft 28 to come to rest. To prevent backward motion a second rail 150, held by a spring 151, is also pivoted on shaft 145 and has a notch 152 adapted to engage a one tooth ratchet 153 fixed to the shaft 28. The feeler mechanism described acts not only to time the label feed with the leading face of the article but also prevents its operation if no article is being delivered.

To keep the labels in constant registration with the cutting mechanism, so that the labels will be severed on the correct line with respect to the printing which they bear, they are preferably provided with perforations or notched edges through which may pass a pin 160 reciprocable through aligned holes 161 in the guide plates 56 (Fig. 9). The pin is carried on an arm 162 fixed on a cross shaft 163. This shaft also carries arm 164 (Fig. 10) drawn by a spring 165 to keep its end in engagement with an adjustable segmental cam 166 on the pawl carrier 76 which drives the label feed rolls 67, 68. The arm 164 also carries a multiple toothed pawl 167 which, when the arm 164 is permitted to rock by the passage of the pin through the web, grasps the holding ratchet as in Fig. 6 and stops further movement of the pawl carrier, which is driven only by the spring 84. The cam, which is adjustably mounted on the pawl carrier by a bolt and slot connection 168, is set so as to hold the pawl 167 out of contact with the holding ratchet during the initial feeding of the label web, and to release the arm 164 to permit the pin 160 to rest on the web as the feeding motion approaches its end. When the pin finally drops into the hole in the paper the feed will stop instantly.

The adjustable cam 166 also has a further use in connection with labels having continuous printing; that is, labels in which there is no recurrent design requiring severance in accurate relationship. By positioning the web around, rather than through, the guides 56, and by setting the cam 166 to terminate the feed a predetermined time after it has been started by cam 65, labels of a constant width may be severed successively from the web and registered with the article by the mechanism driven from feeler 140 as described above.

Certain features of the adjustment of the mechanism to change the size of the label or to accommodate articles of differing sizes will now be considered. For loaves of different lengths no adjustment is necessary except a bodily shift of the labeler frames 170 transversely of the machine. These frames also carry the side belts 25 and 135, which are driven from shaft 35 by a chain 171, gearing 172, and a chain 173, and are mounted for lateral sliding movement on rods 174 and can be adjusted by the usual right and left hand screws 175.

The front margin, that is to say the distance between the front edge of the article and the front edge of the label, is determined by the feeler 140. There is always a definite travel between the time an article strikes the feeler and the time the article meets a label fed between the belts 131, 132. As long as the front margin is to be preserved unchanged this travel is constant, al-

though the relative timing between the labeler and the wrapping machine may vary. If it is desired to change the front margin the position of the member 37 on shaft 28 is altered, as by set screws 176 (Fig. 4), producing an effect equivalent to a shifting of the feeler longitudinally of the conveyor.

No adjustment is provided for varying the rear margin, this being accomplished by changing the size of the printed label or by centering a given label by varying the front margin. In the machine shown there is no provision for adjusting either the bottom or top margins, the former being fixed by the position of the cut off knives and the latter by the height of the labels. The labels being fed vertically their height is varied by the perforations or indentations which cooperate with the pins 160. Whenever the perforations permit the pins to enter, the vertical feed of the label web is arrested, and at the proper time the label will be severed therefrom and fed laterally into contact with a loaf. It is, however, necessary to vary the distance between the registering pins and the cutting point in order that the printed part of the label shall be in proper registration with the knife. This is accomplished by changing the position of roll 51.

The labels are supplied to the machine in web form wound on reels which are mounted with their axes horizontal, thus permitting the use of large reels without a substantial increase in the floor space occupied by the machine. A further advantage of this mounting, coupled with the vertical feed and subsequent lateral transfer of the labels, is that the reels on the two sides may be identical. With a vertical axis of the reel, on the contrary, the web has to be specially printed in right and left hand forms for the two sides.

The wrapper is preferably sealed around the article by heaters 180 on the wrapping machine before entering the labeler, in order to avoid the necessity of supplying through the label itself sufficient heat to melt the wax on the underlying overlapped folds. With printed wrappers this reduction of the heat required assists in preventing smearing, a danger which is further avoided by using the metallic heated belts or chains 135 instead of heated plates past which the articles slide.

50. What we claim is:

1. A method of applying to a wrapper having an external fusible coating a label having a fusible coating on the side next to the wrapper, which comprises heating the wrapper, rolling the label against the still hot wrapper, heating the label while pressing it against the wrapper by pressure normal to the surface thereof to cause its coating to unite with the fused coating of the wrapper, and chilling the wrapper and label.

2. A method of applying labels to overlapped end folds carrying a fusible coating which comprises heating the end folds to fuse the fusible wrapper coating, rolling against the still hot folds a label having a fusible coating on its inner surface, heating the label while pressing it against the folds by pressure normal to the surface of the label, whereby slippage of the label and smearing of ink thereon is avoided, and subsequently chilling the folds and label.

3. A method of applying labels to overlapped end folds carrying a fusible coating which comprises heating the end folds to fuse the fusible wrapper coating, rolling against the still hot folds a label having a fusible coating on its inner surface, heating the label while pressing it against

the folds by pressure normal to the surface of the label, whereby slippage of the label and smearing of ink thereon is avoided, and subsequently chilling the folds and label by pressure normal to the surface of the label.

4. A labeling machine comprising means for forwarding an article, a label web reel mounted at the side of the path of travel of the article with its axis horizontal and transverse to said path of travel, means for feeding the web into a vertical plane intersecting said path of travel, means for severing a label from the web, and means for moving the severed label laterally into contact with the article.

5. A labeling machine comprising means for forwarding an article including an endless pressing member traveling in contact with the surface of the article to be labeled, a pair of label conveying belts positioned to deliver a label between the article and the pressing member, and means for feeding labels between said label conveying belts in timed relation to the article.

6. A labeling machine comprising means for forwarding an article including an endless pressing member traveling in contact with the surface of the article to be labeled, a pair of label conveying belts in label gripping contact one with the other and extending substantially transversely to the path of travel of said pressing member, and guide rolls for the two belts positioned with their axes spaced apart in a plane substantially transverse to said path of travel to direct a label between the article and the pressing member, and means for feeding labels between said label conveying belts in timed relation to the article.

7. A labeling machine comprising a pair of belts disposed on each side of the path of motion of the articles and adapted to grasp the articles between them, means to drive the belts to forward the articles so grasped, and means to deliver labels between a belt and the corresponding end of the article in timed relation to the passage of the article.

8. A labeling machine comprising a pair of metallic belts disposed on each side of the path of motion of the articles and adapted to grasp the articles between them, means to heat the belts, means to drive the belts to forward the articles so grasped, and means to deliver heat sealing labels between a belt and the corresponding end of the article in timed relation to the passage of the article.

9. A labeling machine comprising means for forwarding an article along a horizontal path, a pair of feed rolls having their axes horizontal and transverse to said path, means for supplying a label web to said rolls, means for rotating the rolls intermittently in a direction to feed the label web upwardly with the uppermost label thereon in vertical alignment with the article, means for severing the uppermost label from the web, a pair of rotating feed rolls positioned above the first pair with their axes vertical, means for moving said latter rolls first apart to receive the web from the first rolls and then together to grasp and feed laterally the label severed from the web, and means to apply to the article the label so fed.

10. A labeling machine comprising means for forwarding an article along a horizontal path, a pair of feed rolls having their axes horizontal and transverse to the path, means for supplying a label web to said rolls, means for operating said rolls to feed the label web upwardly with

the uppermost label thereon in vertical alignment with the article, means for severing the uppermost label from the web, a pair of intermittently engageable feed rolls positioned above the first pair with their axes vertical, and means to actuate said latter feed rolls to grasp the severed label and shift it transversely of the web in a direction towards the article for application thereto.

10. 11. A labeling machine comprising means for forwarding an article along a horizontal path, a pair of feed rolls having their axes horizontal and transverse to said path, means for supplying a label web to said rolls, means for rotating the rolls intermittently in a direction to feed the label web upwardly with the uppermost label thereon in vertical alignment with the article, means for severing the uppermost label from the web, a pair of rotating feed rolls positioned above the first pair with their axes vertical, means for moving said latter rolls first apart to receive the web from the first rolls and then together to grasp and feed laterally the label severed from the web, a detector actuated by the passage of an article for initiating the closing movement of the latter rolls, and means to apply to the article the label so fed.

12. A labeling machine comprising means for forwarding an article along a horizontal path, a pair of feed rolls having their axes horizontal and transverse to said path, means for supplying a label web to said rolls, means for rotating the rolls intermittently in a direction to feed the label web upwardly with the uppermost label thereon in vertical alignment with the article, means for severing the uppermost label from the web, a pair of rotating feed rolls positioned above the first pair with their axes vertical, means for moving said latter rolls first apart to receive the web from the first rolls and then together to grasp and feed laterally the label severed from the web, a detector actuated by the passage of an article for initiating the closing movement of the latter rolls, and means to apply to the article the label so fed.

13. A labeling machine comprising means for forwarding an article, mechanism for feeding a label into contact with the article being so forwarded at a predetermined point in its travel, a detector actuated by the passage of an article past a preceding point in its travel, connections between said detector and said mechanism to initiate the operation thereof a predetermined time before the article arrives at the first of said points, and means for varying the duration of said predetermined time independently of the passage of an article past the detector to vary the registration of a label applied to the article by said mechanism.

14. A labeling machine comprising means for forwarding an article, a label web reel mounted at the side of the path of travel of the article with its axis horizontal and transverse to said path of travel, means for feeding the web into a vertical plane intersecting said path of travel, mechanism for adjusting the length of web so fed, means for severing a label from the web, and means for moving the severed label laterally into contact with the article.
